SYSTEM OF CODING AND DECODING

Walter S. Lemmon, New York, Clyde J. Fitch, Endicott, and Richard F. Walz, New York, N. Y., assignors to International Business Machines Corporation, New York, N. Y., a corporation of New York

Application September 5, 1935, Serial No. 39,294

9 Claims. (CL 35—4)

This invention relates to the art of secret writing and more particularly to a new system for transforming language messages into decodable secret code.

An object of the present invention is to provide an improved system for the more rapid and accurate coding and decoding of characters or signs used in various communications.

Another object of the invention is to prevent periodical recurrences by causing irregularities in the coding process by a new system so as to introduce a new order of complexity of code according to an arbitrary system.

A further object of the invention is to produce a resultant which is most complex but whereby the coding and decoding operations are simplified.

Heretofore, in order to prevent periodical recurrences in forming unintelligible sequences of characters in a coded message and to insure a continuous variation and transposition of the resultant character form, the electrical systems producing such effects, at present, employ a plurality or multiplicity of coding drums or wheels which are adapted to be actuated differentially to alter the circuit connections of the system. It has been found that systems of this type are apt to become quite complicated and tend to reduce the overall rate of speed of operation of the system.

In contradistinction to the present systems, the invention to be disclosed embodies a single coding drum or wheel, acting as a circuit connection changing device to which, at variable times, a definite movement is imparted to alter, at irregular intervals, the circuit connections of the system. For the purpose of obtaining operation at irregular intervals of the code wheel an electrical circuit arrangement of varying pattern is employed which shifts the coding circuits aperiodically.

More specifically, for illustrative purposes a plurality of well known distributing or rotary switches are used, the contacts of which are connected in an arbitrary manner to provide innumerable cycles of operation thereof without incurring or repeating a similar circuit pattern or arrangement.

A further feature of the present invention is the provision of simple and automatic means of restoring the controlling circuit arrangements and the coding circuits to the normal starting position.

Further and other objects and advantages will be hereinafter set forth in the accompanying specification and claims, and shown in the draw-

ing, which by way of illustration shows what is now considered to be the preferred embodiment of the invention.

In the drawing the circuits are shown embodying one preferred form of the present invention.

Referring to the drawing, a well known form of coding drum or wheel arrangement is shown diagrammatically and generally indicated by the reference character 10. Two groups of contacts 11 and 12 are shown to engage a multi-segment drum or commutator ring 13 partly developed. The group of contacts 11 are arranged to engage permanently the associated segments 13—a, whereas the group of contacts 12 are adapted to be positioned with respect to the drum segments 13—a at irregular intervals upon energization and release of the associated electromagnet R—5.

It is deemed unnecessary to describe the code drum further in detail, since a complete description and disclosure of the code drum is set forth in a copending application Serial No. 730,905 filed June 16, 1934, and wherein the electromagnet R—5 is designated 155 and adapted to position the contacts 39, corresponding to the said contacts 12 in the present disclosure, with respect to the commutator ring 41 (corresponding to the ring 13 in the present drawing) and contacts 42 corresponding to present contacts 11.

Controlling instrumentalities, such as key bars 14 are connected to the contacts 11, so that upon depression of an individual character key the associated contacts 15 connect grounded battery 16 to the corresponding contact 11 and associated segment 13—a to energize the connected circuit through the corresponding contact 12 engaging the same said segment 13—a, and the control element embodied therein, for example, the solenoid 17, effecting depression of a controlling key bar 18 and recording the selected code character.

The controlling instrumentalities 14 and 18 may comprise the key bars of a typewriter or punch to record the coded character. It is obvious that the remaining character keys of a standard typewriter, one form of which is described in the above mentioned application, may be connected to additional segments 13—a in the manner shown in the simplified accompanying diagram.

The preferred form of the invention at present is adapted to energize the magnet R—5 at irregular intervals causing a displacement of the brushes 12 and will now be described.

A plurality of distributing or rotary switches 21 to 24 inclusive are provided to form and complete various electrical circuit patterns to control the

energization of magnet R-5 in such a manner as to prevent periodical recurrences of the same electrical pattern. It will become obvious as the description progresses that additional distributing switches can be provided to further complicate the resultant circuit pattern without departing from the broad scope of the present invention.

The distributing switches 21 to 24 inclusive are a well known standard type of rotary switches 10 and are similar in design to the selector switches used in telephonic systems and comprise in general shafts 21s to 24-s, electromagnets R-1 to R-4 for rotating the associated shafts one step at a time, a plurality of brushes 21a to c, 22a to c, 15 etc., insulatively mounted upon the associated shafts, and arcuate banks of stationary contacts 21-ca to cc, 22-ca to cc, etc. adapted for cooperation with said brushes. In the specific embodiment the arcuate banks are shown to have 20 twenty-five stationary contacts however this number of contacts can be increased or decreased as seen fit for the particular application.

It is to be noted that the two banks of arcuate contacts of each switch are connected similarly 25 and function only when the "homing circuits" are energized to position the switch brushes to the home or normal position as shown in the drawing. These circuits will be described hereinafter.

The electromagnet R-1 associated with the 30 switch 21 is adapted to be energized upon the depression of each character key of the controlling typewriter or keyboard T-1 upon which the intelligible sequence of characters are selected to be coded by another device T-2 which 35 may be a typewriter similar to T-1.

Contacts 25 are provided for this purpose and are closed upon the depression of each character key 14 of the typewriter T-1. Specific mechanism for this provision is not shown since it is 40 old and well known in the art; one method, which has been used heretofore, is to provide a common bar beneath the key bars of the typewriter and arranged so that the depression of the character keys lowers the common bar which in turn causes 45 the common contacts to be closed.

Closure of contacts 25 connect grounded battery 26 to the electromagnet R-1, energizing the magnet to effect rotation of the brush shaft 21-s to step the brushes 21-a to c ahead to engage 50 the next adjacent contacts in the associated arcuate banks.

It is well to state here that the third bank of contacts 21-cc to 23-cc of switches 21 to 23 and the contacts 24-cc to 24-cc in the banks of 55 switch 24 and the associated circuits therewith form the control circuits to irregularly and arbitrarily energize the magnet R-5 and position the contacts 12 thereby altering the circuit connections between the units T-1 and T-2 effecting 60 a change in the sequence of the recorded characters accordingly. The arcuate banks of contacts forming the control means for magnet R-5 are shown to be connected to form one particular form of circuit pattern, for example, the contacts 21-cc of switch 21 are connected so that 65 upon every fifth character selected the contacts in the said bank are live, however, it is obvious that the contact connections may be altered so that other contacts are live to control 70 additional distributing switches accordingly.

Similarly the connections of the contacts in the remaining banks of the control circuits may be altered so as not to correspond to the connection pattern disclosed in the drawing and therefore 75 it must be understood that the exact connections

of the disclosure are merely one illustrative set of connections possible to be embodied in the present invention.

The contacts 21-cc are connected by a common conductor 27 to the brush 24-d of distributing switch 24. The contacts 24-cd of the fourth bank of switch 24 are irregularly connected so that a predetermined number are connected by common conductors 28 to magnet R-2 and the remaining contacts are connected by common conductor 29 to magnet R-3. Relays RL-2 and RL-3 are also connected to the common conductors 28 and 29 respectively, the purpose of which will be understood presently.

From the description set forth thus far, it is 15 understood that upon depression of any character key 14, contacts 25 are closed to permit battery 26 to energize magnet R-1. Brushes 21-a to c are stepped ahead each time the magnet is operated to engage the associated contacts 21-ca to cc. Engagement of the connected contacts 21-cc permits current to flow from grounded battery 30, brush 21-c, conductor 27, brush 24-d, connected contacts 24-cd, and either to conductor 28 or 29 to energize magnet R-2 and 25 relay RL-2 or magnet R-3 and relay RL-3, respectively, depending upon the position of brush 24-d. From the brush position shown in the drawing the magnet R-2 and Relay RL-2 would be energized. Energization and release of magnet R-2 causes the associated brushes 22a to c to be stepped ahead to engage the adjacent contacts 22-ca to cc.

Energization of relay RL-2 opens the associated contacts 31 disconnecting magnet R-2 35 from conductor 28. Relay RL-2 remains energized so long as battery 30 is connected to the particular and associated contact 24-cd, preventing further energization of magnet R-2.

Assume now that operation of the said magnet R-2 advanced the brushes 22-a to c from the 40 contacts 22-ca to cc shown to be engaged in the drawing to the corresponding adjacent contacts. Referring now to the third bank of contacts 22-cc grounded battery 30 is connected by brush 22-c, to the engaged contact 22-cc, common 45 conductor 32 to contacts 24-cc of switch 24 (third arcuate bank of contacts) brush 24-c, conductor 33 to relay RL-5 and by the conductor 34 to magnet R-5. It was mentioned hereinbefore that upon energization and release of magnet R-5, the group of contacts or brushes 12 associated with the disk segments 13-a are advanced or positioned so as to alter the circuit connections between typewriters T-1 and T-2. 50

It is well to mention at this time, but the purpose thereof to be completely described hereinafter, that brush 35 is also adapted to be advanced one step each time magnet R-5 is operated to engage the adjacent contact 36. The shaft 37 of the brush 35 corresponds to shaft 37 of the aforementioned application, so that it is obvious each time the shaft 37 is rotated a step upon operation of magnet R-5 both the group of brushes 12 and brush 35 are advanced, and 65 in view of the complete description in the said application, this brief description is sufficient.

Energization of relay RL-5 operates the associated and normally closed contacts 38 to disconnect magnet R-5 from the conductor 33 and thereby preventing further energization of the magnet so long as battery 30 is connected to the particular said contact 22-cc (namely, the second contact in the arcuate bank).

It is evident from the wiring connections shown 75

in the drawing, that each time the brush 21-c engages a connected contact the conductor 27 and connected brush 24-d are energized and so long as the first contact 24-cd of the arcuate bank is engaged by the associated brush relay RL-2 and magnet R-2 are energized. Energization of relay RL-2 opens the associated contact 31 deenergizing magnet R-2 and brushes 22-a to c are advanced one step. Obviously, when the advanced brush 22-c engages a connected contact relay RL-5 and magnet R-5 are energized either through conductor 32 or conductor 39. During the completion of the fifth cycle of brush 21-c, magnet R-2 will be operated to step the brushes 22-a to c to the twenty fifth contacts of the arcuate banks, so that battery 30 is connected now by the brush 22-c, conductor 40, contact 24-ce, brush 24-e and conductor 41 to energize relay RL-4 and magnet R-4. Operation of magnet R-4 now steps its brushes ahead one contact. Relay RL-4 remains energized to disconnect magnet R-4 from conductor 41 for the same purpose as explained with respect to relays RL-2 and RL-3, namely to prevent the R-4 magnet from further energization. Upon completion of another cycle brush 22-c again connects battery 30 to the same circuit just described to energize magnet R-4 and the associated relay RL-4, thereby advancing the associated brushes to the third contacts of the arcuate banks.

Whereupon, further engagement of the connected contacts 21-cc by brush 21-c, battery 30 is connected to conductor 27, brush 24-d, third contact 24-cd, conductor 29 to energize magnet R-3 and the associated relay RL-3, thereby advancing brushes 23-a to c.

Upon the completion of a cycle of the brushes of switch 23, battery 30 is connected by brush 23-c, to conductor 42, third contact 24-ce, brush 24-e and conductor 41, energizing magnet R-4 and advancing the associated brushes one step.

Without further detailed description of the said circuits it is evident that upon completion of a number of cycles by brush 21-c, brush 22-c is advanced to energize at irregular intervals magnet R-5 and alter the circuit connections between units T-1 and T-2.

Similarly, upon complete cycles of operation of brush 22-c, magnet R-4 is energized to alter the circuit pattern by connecting switch 23 in the magnet R-5 controlling circuit. And upon completion of a number of cycles of brushes 23-a to c, operation of magnet R-4 causes switch 22 to be inserted in the said control circuit for magnet R-5. It is self-evident from the description just set forth, that additional switches similar to switches 21 to 24 inclusive may be added to increase the number of permutations generated by the altering circuit pattern, so as to render the resultant message coded by typewriter T-2 quite complex that the message resistance is so great as to render it practically impossible to decipher the said resultant.

To render it possible to decode the resultant coded message by the units T-1 and T-2, that is to select the sequence of unintelligible characters by the keys 14 of unit T-1 and record the intelligible sequence of characters on unit T-2, it is necessary before decoding to have the circuit changing devices all in the same normal or home position that the units occupied before coding the message.

75 Provision has been made to reset automatically

all the units, such as brushes 21-a to c, 22-a to c, etc. and contacts 12 and brush 35, to the normal home position, namely, the position of the said units as indicated in the drawing, and will not be described.

Depression of the "homing" key 45 momentarily connects grounded battery 46 to relay 47, energizing the relay to operate the associated contacts 48, 49 and 67. Let it be assumed that upon the completion of coding the message all the displaceable units, namely brushes 21-a to c, etc. and contacts 12 and brush 35, have been positioned so that each unit is displaced from the normal position as indicated in the drawing.

Therefore, operation of contacts 48 permits grounded battery 50 through any connected contact 21-cb, brush 21-b, and conductor 51 to continue to energize relay 47 and thus acts as a locking circuit arrangement for the said relay. In conjunction with relay 47, it should be mentioned here, that the relay is a slow release relay, so that the associated contact 48 remains closed or operated for a timed interval equivalent to the time necessary for the brush 21-b to be advanced to an adjacent associated contact.

Operation of contacts 49 connects the grounded battery 46, by conductor 52, brush 21-a and associated contact 21-ca through normally closed contacts to magnet R-1, energizing the magnet to advance the brushes 21-a to c. Advancement of the brushes, irrespective of the position of brushes 22-a, 23-a, etc. will not open the lock circuit through contact 48 due to the slow release feature of relay 47.

Energization of magnet R-1 also operates the normally closed contacts 53, deenergizing magnet R-1, to permit subsequent energization through another contact 21-ca, etc. until the brushes 21-a to c have been advanced to the normal position as indicated. Grounded battery 46 is now connected through brush 21-a, the first contact 21-ca to brush 22-a energizing magnet R-2 to advance the associated brushes and similarly due to the interrupting contacts 54 magnet R-2 is energized successively until set to the home position whereupon magnets R-3 and R-4 are energized successively, and individually in a similar manner to reset the associated brushes, respectively, to normal. The brushes of the second bank of each of the switches and the associated connected contacts act, as explained before, as the holding circuit for relay 47.

Therefore, it is evident upon the completion of resetting all the brushes 21-b, 22-b, 23-b and 24-b to the normal position, (namely, the first contact of the respective arcuate bank of contacts), battery 50 is disconnected from all the said brushes, thereby preventing further energization of relay 47 through the associated contact 48, and thus restoring relay 47 to the normal position shown in the drawing.

The said momentary depression of key 45 also permits the grounded battery 46 to energize relay 55, to operate the associated contacts 56, 57 and 66. Operation of contacts 56 connects grounded battery through the contacts 59 (which are closed at all times when the contacts 12 and brush 35 are not in the normal home position) and conductor 60 to maintain relay 55 energized and acts as a locking circuit for said relay. Grounded battery 46 is then connected through closed contacts 57, conductor 61, and normally closed contacts 62 to energize magnet R-5. Through the operation of the interrupting contacts 62 magnet R-5 is energized successively to

step the shaft 37 ahead with the associated group of contacts 12 and brush 35 until the contacts 12 and brush 35 are reset to the normal position. The connected contact 36 of the segmented ring 5 indicates the normal position, and the brush 35 upon engaging the said contact 36 completes a circuit from grounded battery 58 to energize relay 65 operating contacts 59 to open the locking circuit for relay 55, thereby disconnecting battery 10 66 from the said circuits just traced. Relay 65 is a fast operating relay and breaks the contacts 59 to cause deenergization of relay 55 before the magnet R-5 can be energized, therefore once the contacts 12 and brush 35 have been reset to 15 home position, further actuation of the said contacts and brush by subsequent energization of magnet R-5 cannot be effected to cause a faulty positioning of the units.

It was mentioned that operation of relays 55 20 and 47 also operated the normally closed contacts 66 and 67 respectively.

The operation of the said contacts prevents the grounded battery to be connected to any of the brushes 21-c, 22-c and 23-c as explained 25 in conjunction with the coding or decoding operation so as to prevent faulty energization of magnet R-5. Upon deenergization of the said relays 55 and 47 the contacts in the normally closed position permit the grounded battery 30 30 to be connected to the said brushes to function as explained hereinbefore.

It has been shown how the stepping or displaced units may be returned to the normal position after either a completed coding or decoding 35 function to permit subsequent similar function of the device.

It has also been shown that the displaceable contacts 12 are positioned at irregularly and arbitrarily timed intervals depending entirely 40 upon the pattern of the connections of the described electrical circuits, thus effecting the sequence of the recorded characters on the secondary unit T-2 which is in accordance with the aperiodic changes of the connections of the interconnecting circuits from the primary unit 45 T-1 through contacts 11, segments 13-a, and movable contacts 12 to unit T-2.

While there has been shown and described and 50 pointed out the fundamental novel features of the invention as applied to a single modification it will be understood that various omissions and substitutions and changes in the form and details of the device illustrated and in its operation 55 may be made by those skilled in the art without departing from the spirit of the invention. It is the intention, therefore, to be limited only as indicated by the prior art and the scope of the following claims.

60 What is claimed is:

1. A coding and decoding machine comprising a manually operable primary machine, a secondary machine operable from the first, coding means comprising a single movable circuit changing device connecting the machines to control operation of the secondary machine from the primary machine including a series of electrical circuits, each adapted to be selectively closed by operation of the primary machine, means to position the coding means to transpose the said series of circuits interconnecting the machines, and a plurality of interconnected electrical control means under control of the primary machine to control the said positioning means at irregular and arbitrary intervals, thereby altering the posi-

tion of the coding means and transposing the said interconnecting circuits.

2. A coding and decoding machine comprising a manually operable primary machine, a secondary machine operable from the first, coding means comprising a movable circuit changing device connecting the machines to control the operation of the secondary machine from the primary machine including a series of electrical circuits, each adapted to be selectively closed by 10 operation of the primary machine, means to position the coding means to transpose the said series of circuits interconnecting the machines, and a plurality of control circuits, a predetermined number of which are energized upon each operation of the primary machine, the remaining control circuits being controlled by the said predetermined number, all of the said control circuits interconnected to control the positioning means of the circuit changing device at irregular and 20 arbitrary intervals.

3. A coding and decoding machine comprising a manually operable primary machine, a secondary machine operable from the first, coding means comprising a movable circuit changing device 25 connecting the machines to control the operation of the secondary machine from the primary machine including a series of electrical circuits, each adapted to be selectively closed by operation of the primary machine, means to position the coding means to transpose the said series of circuits interconnecting the machines, and a plurality of control units, a predetermined number of which are operated at certain intervals during the operation of the said primary machine, the remaining control units adapted to be operated at other and different intervals during the operation of the primary machine, all of the said control units interconnected to control the positioning means of the circuit changing device at irregular and 30 arbitrary intervals.

4. A coding and decoding machine comprising a manually operable primary machine, a secondary machine operable from the first, coding means comprising a single movable circuit changing device connecting the machines to control the operation of the secondary machine from the primary machine including a series of electrical circuits, each adapted to be selectively closed by 45 operation of the primary machine, means to position the coding means to transpose the said series of circuits interconnecting the machines, and a plurality of units comprising rotary switches controlled by the primary machine to control the positioning means of the circuit changing device 50 at irregular and arbitrary intervals.

5. A coding and decoding machine comprising a manually operable primary machine, a secondary machine operable from the first, coding means comprising a movable circuit changing device connecting the machines to control the operation of the secondary machine from the primary machine including a series of electrical circuits, each adapted to be selectively closed by 60 operation of the primary machine, means to position the coding means to transpose the said series of circuits interconnecting the machines, and a plurality of electro-magnetic devices, a predetermined number of which are operated upon each operation of the primary machine, the 65 remaining electromagnetic devices adapted to be controlled by the said predetermined number, all of said devices interconnected to control the positioning means of the circuit changing device at 70 irregular and arbitrary intervals.

6. The invention set forth in claim 3 in which the said control units comprise relay devices with associated contacts which are arbitrarily interconnected so that upon each operation thereof 5 the contacts complete circuit connections of varying pattern.
7. The invention set forth in claim 3 in which means are provided to reset the movable circuit changing device and control units to a normal 10 initial position whenever displaced therefrom by the operation of the positioning means.
8. A coding and decoding machine comprising a manually operable primary machine, a secondary machine operable from the first, coding 15 means comprising a movable circuit changing device connecting the machines to control the operation of the secondary machine from the primary machine including a series of electrical circuits, each adapted to be selectively closed 20 upon operation of the primary machine, means to position the coding means to transpose the said series of circuits interconnecting the machines, and a plurality of interconnected control circuits, and means to selectively energize at different intervals 25 the said control circuits to control the positioning means of the circuit changing device at irregular and arbitrary intervals.
9. A coding and decoding machine comprising a manually operable primary machine, a secondary machine operable from the first, coding 5 means comprising a movable circuit changing device interconnecting the machines to control the operation of the secondary machine from the primary machine, including a series of electrical circuits, each adapted to be selectively closed by 10 operation of the primary machine, means to position the coding means to transpose the said series of circuits interconnecting the machines, control means actuated upon each operation of the said primary machine, and additional control 15 means associated with the first mentioned control means and controlled thereby, means to actuate at various intervals the said additional control means during the operation of the primary machine to control the said positioning means at 20 irregular and arbitrary intervals.
